(57) **CLAIM**

The ornamental design for an elbow support, as shown and described.

DESCRIPTION

FIG. 1 is a front perspective view of an elbow support showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof, showing the front flap in an open condition; and,

FIG. 9 is a partial front perspective view thereof, showing the elbow support wrapped around an elbow in condition of use. It is understood that the broken lines within the claimed design indicates stitch lines, which form part of the claim. The broken lines showing an arm in FIG. 9 illustrates environmental structure and forms no part of the claimed design.
